UNITED STATES PATENT OFFICE.

FRANKLIN L. BARBER AND EDWIN W. WEBB, OF CHICAGO, ILLINOIS, ASSIGNEES TO
STANDARD CAR TRUCK COMPANY, OF CHICAGO, ILLINOIS, A CORPORATION OF
NEW JERSEY.

SPRING-EQUALIZED TRUCK.

1,106,027.

Specification of Letters Patent.

Patented Aug. 4, 1914.

Application filed May 25, 1914. Serial No. 840,736.

To all whom it may concern:

Be it known that we, FRANKLIN L. BARBER and EDWIN W. WEBB, citizens of the United States, residing at Chicago, in the county of Cook and State of Illinois, have invented certain new and useful Improvements in Spring-Equalized Trucks; and we do hereby declare the following to be a full, clear, and exact description of the invention, such as will enable others skilled in the art to which it appertains to make and use the same.

Our invention relates to car trucks, and has for its especial object the provision of a spring equalized caboose truck.

Generally stated, the invention consists of the novel devices and combinations of devices hereinafter described and defined in the claims.

In the accompanying drawing which illustrate the invention, like characters indicate like parts throughout the several views.

Referring to the drawings: Figure 1 is a side elevation showing the truck with the wheels and journal box removed; Fig. 2 is a plan view of the parts shown in Fig. 1, some parts being broken away; Fig. 3 is a vertical section taken on the line $x^3 x^3$ on Fig. 1, some parts being broken away; Fig. 4 is a horizontal section taken on the line $x^4 x^4$ on Fig. 1, and Fig. 5 is a fragmentary view showing portions of the truck in side elevation.

It may be here stated that the salient novel feature of the improved truck herein disclosed and claimed is the arrangement whereby an equalized truck with double acting springs is obtained without the use of equalizing bars or pedestal journal boxes.

The side frames 1 of the truck are preferably of cast steel with frame extensions 2 which rest on the journal boxes and support the frame and its load from the journal boxes. The journal boxes are not shown, but would be located between the frame extensions 2, and a T strap 3, that are formed from flat bars reduced at their inner ends and passed through holes in depending portions of the frame and secured thereto by nuts 4.

As shown, the cast side frames 1 are formed with openings 1^a, 1^b, and 1^c. The openings 1^c are simply to give lightness to the frame, but the openings 1^a and 1^b perform other and more important functions.

The openings 1^b have extended brackets or spring seats cast integral with the truck side frames to receive and hold the base of coiled springs 5 that are surmounted by saddle caps 6 to which they are pivotally connected. On the outer and inner sides of the truck side frames 1, are solid link hangers 7, the upper ends of which are pivotally connected in pairs to the upper ends of the saddle caps 6, by means of pins 8. The lower ends of the pairs of links 7 carry jib pins 10 on which rest the ends of elliptical equalizing springs 11.

The laterally spaced side frames 1 are rigidly connected by cross transoms 12 located in the lower corners of the openings 1^a and riveted to adjacent flanges of the said side frames. The flanged upper portions of the sides of the frame openings 1^a afford columns 1^d, between which the ends of the truck bolster 13 are arranged to work with freedom for limited endwise movements of said bolster transversely of the truck. The bolster does not directly engage with the faces of the columns 1^d but directly engages with channel-shaped guide pieces 14, which, in turn, work vertically on the faces of the said columns, but by their channel-shaped form are held against movements with the bolster transversely of the truck. The endwise movements of the bolster are limited, as shown, by stop flanges 15 on the ends thereof, and which engage with the guide pieces 14. The said guide pieces 14 have lips 16 that rest upon, and vertical ribs 17 that interlock with the end portions of a combined spring cap and roller base 18, which latter has a flanged piece seated upon the hub 11^a of the coöperating equalizing spring 11.

Lateral motion bearing rollers 19 are interposed between the ends of the bolster 13 and the underlying spring cap and roller bases 18, and the said members 13 and 18 are provided with the customary, or any suitable form of concave seats, whereby the bolster is yieldingly held in an intermediate centered position.

By reference particularly to Fig. 3, it will be noted that equalizing springs 11, in the preferred arrangement illustrated, are arranged in pairs, one inside and the other outside of the coöperating side frame 1. This gives a wide lateral support for the

combined spring cap and roller base 18 and also keeps the springs close to the side frames. Furthermore, this duplex arrangement of the said springs and of the links 7, 5 transmits the weight centrally to the coiled springs 5 and to the truck side frames.

The so-called slides 14 are preferably in the form of castings but may be otherwise formed. When worn, they may be readily 10 replaced; and furthermore, they permit the bolster, when on its side, to be passed through the openings in the frame and turned to position, without requiring wide openings below the column guide faces. The 15 guide pieces 14 should be inserted after the bolster is in place. Each hanger made up of the solid links 7, might, as is obvious, be made up of a single U-shaped piece. As shown, brake hangers 20 are cast integral 20 with the truck side frames, but this is a feature which constitutes no part of the present invention.

The truck, while especially designed as a caboose truck, may, nevertheless, as is obvious, be generally used wherever found serviceable.

What we claim is:

1. In a car truck, the combination with truck side frames having columns, of combined spring caps and roller bases, spring-supported on said side frames, a truck bolster with its ends working between said columns, rollers interposed between said bolster, and combined spring caps, and roller bases, and guide pieces carried by said combined spring caps and roller bases, interposed between said columns and bolster and movable vertically on said columns, said bolster having an endwise movement, in respect to said guide pieces, transversely of the truck.

2. In a car truck, the combination with truck side frames having columns, of combined spring caps and roller bases spring-supported on said side frames, a truck bolster with its ends working between said columns, rollers interposed between said bolster and combined spring caps and roller bases, and guide pieces detachably supported by said combined spring caps and roller bases, interposed between said columns and bolster and movable vertically on said columns, said bolster having an endwise movement, in respect to said guide pieces, transversely of the truck.

3. In a car truck, the combination with side frames having columns, of combined spring caps and roller bases spring-supported on said side frames, a bolster with 50 its ends working between said columns, lateral motion rollers interposed between said bolster and combined spring caps and roller bases, and channel-shaped guide pieces interposed between said bolster and columns

and movable vertically on the latter, said 65 guide pieces, at their lower ends, having ribs and supporting lips that detachably interlock with the ends of the combined spring caps and roller bases.

4. In a car truck, the combination with 70 truck side frames having columns, of front and rear springs mounted on said side frames, longitudinally extended equalizing springs, hangers connecting the ends of said equalizing springs to the said front and rear 75 springs, and a bolster working between the columns of said side frames and supported on the intermediate portions of said equalizing springs.

5. In a car truck, the combination with 80 truck side frames having columns, of front and rear coiled springs seated on said side frames, elliptical equalizing springs extending longitudinally of said side frames to the front and rear of said columns, hangers carried by said coiled springs and connected to the ends of corresponding equalizing 85 springs, and a truck bolster working between said columns and carried by the intermediate portions of said equalizing springs. 90

6. In a car truck, the combination with truck side frames having columns, of front and rear coiled springs seated in openings in said side frames, elliptical equalizing 95 springs extended longitudinally of said side frames, hangers carried by said coiled springs and connected to the ends of said equalizing springs, a truck bolster carried on the intermediate portions of said equalizing springs, and lateral motion devices 100 interposed between said equalizing springs and bolster.

7. In a car truck, the combination with truck side frames having columns, of front and rear coiled springs seated in openings 105 in said side frames, equalizing springs arranged in pairs extended longitudinally of said side frames, one on the inner and the other on the outer side thereof, hangers carried on said coiled springs and having arms, 110 both on the inner and outer sides of said side frames, connected at their lower ends to the ends of said pairs of equalizing springs, and a truck bolster working between said columns and carried by the intermediate 115 portions of said equalizing springs.

8. In a car truck, the combination with truck side frames having columns, of front and rear coiled springs seated in openings 120 in said side frames, equalizing springs arranged in pairs extended longitudinally of said side frames, one on the inner and the other on the outer side thereof, hangers carried on said coiled springs and having arms, 125 both on the inner and outer sides of said side frames, connected at their lower ends to the ends of said pairs of equalizing

springs, a bolster working with a limited
endwise movement between said columns,
combined spring caps and roller bases sup-
ported on the intermediate portions of said
5 equalizing springs, and rollers interposed
between said bolster and combined spring
caps and roller bases.

In testimony whereof we affix our signa-
tures in presence of two witnesses.
